UNITED STATES PATENT OFFICE.

CHARLES HASLETT, OF BUTLER, PENNSYLVANIA.

MEANS FOR ODORIZING GAS.

SPECIFICATION forming part of Letters Patent No. 340,310, dated April 20, 1886.

Application filed December 23, 1885. Serial No. 186,533. (No model.)

To all whom it may concern:

Be it known that I, CHARLES HASLETT, a citizen of the United States, residing at Butler, in the county of Butler and State of Pennsylvania, have invented certain new and useful Means for Odorizing Gas; and I do hereby declare the following to be a full, clear, and exact description of the invention, reference being had to the accompanying drawing, which forms part of this specification.

The object of my invention is to provide a method and means for imparting an artificial and easily-perceptible odor to combustible and explosive gases, in order that the presence 15 of the gas in cellars and other localities wherein leakage-gas may accumulate may be easily detected and proper precautions adopted to prevent its ignition from accidental causes.

My invention is particularly adapted to systems for the distribution and supply of natural gas. As is well known, natural gas is almost deficient in odor, while at the same time it is of such a subtle character that leakage in the supply-pipes and fittings is of very frequent occurrence. The leakage-gas accumulates in 25 cellars and apartments, and, being imperceptible, affords of itself no means of detecting its presence; hence disastrous accidents are liable to take place at any time should any 30 light or flame be brought in the neighborhood, as the gas, being mixed with sufficient air, is highly explosive and very easily ignited.

My invention consists in the novel appliances for odorizing the natural gas while the 35 same is passing through the supply-pipes.

The apparatus consists of devices for supporting or holding the solid odorizing material in such a position that the gas can pass freely over its particles, and so that access can 40 be readily had to the odorizing material, for the purposes of renewal, replacement, or rearrangement.

In carrying my invention into effect I employ, by preference, as the odorizing substance 45 or medium the ordinary gum-camphor of commerce, and incase the same in wire, perforated, or open-work baskets, tubes, or the like, which I arrange within the gas-conveying tubes under such conditions that the gas 50 will pass over and in contact with the contents of the tubes or casings holding the odorizing substance and become thoroughly im-

pregnated with the latter. The gas, therefore, supplied to the points or localities for consumption will be of a highly-odorous quality, 55 and should there be any leakage the existence thereof will be at once perceived, so that precautions may be taken to avoid explosion.

In the accompanying drawing, representing an apparatus for carrying my invention into effect, I have shown in section a series of connections or sections of pipe coupled together by T-couplings and elbow-joints, with the wire baskets or open tubes containing the odorizing substance arranged in different sections.

A designates a low-pressure main, and B a supply-pipe leading therefrom to a house or building to be supplied.

The odorizing apparatus may be located at 70 any point of the supply-pipe, and may consist of a series of short sections of tubing, C C C, united and communicating through and by the couplings D D, sleeves E E, and short tubes F.

G G G G designate wire baskets or tubes, preferably closed on both ends, the tops having wire caps g g. These tubes or baskets are filled or partially filled with any suitable odorizing substance in a solid condition; but, 80 after experiment, I have adopted, by preference, gum-camphor, which will readily impart its pungent and penetrating odor to the gas and render the latter odorous to all required degrees. The camphor will last for an indefinite time, and is comparatively inexpensive. At the same time, while it serves perfectly as an odorizing element, it does not in any degree lessen or affect the combustible properties of the gas.

The tubes or baskets G G are arranged within the sections C C, nearly filling the same, but allowing sufficient space for the gas to pass freely through the pipes.

In practice the tubes containing the odorizing substance should be sufficiently larger in diameter than the balance of the supply-pipe to compensate for the filling within the former and allow the gas to pass through without additional friction.

The gas may be odorized while passing through the supply-pipes, or it may be odorized at any point of its transit from the well.

So, too, the odorizing apparatus may be

located at any convenient point or position, and, if desirable, within the building to be supplied.

To give ready access to the contents of the odorizing apparatus, the tubes C C are provided with screw-caps H H, which may be removed.

Having described my invention, what I claim, and desire to secure by Letters Patent, is—

1. A gas-odorizing apparatus consisting of a removable wire or open-work basket or casing containing gum-camphor or other odorizing substance located in the main or supply pipes of a gas conveying or supplying system, substantially as described.

2. The gas-odorizing apparatus herein described, consisting of a series of connected and substantially parallel tubular sections containing wire baskets or open-work casings or tubes adapted to contain gum-camphor or other odorizing substance, and arranged substantially as described. 20

In testimony that I claim the foregoing I have hereunto set my hand this 21st day of 25 December, 1885.

CHARLES HASLETT.
